LOCAL VIBRATOR FOR CONCRETE

Nicola Andriani, Rome, Italy

Application May 16, 1955, Serial No. 508,660

Claims priority, application Italy May 14, 1954

5 Claims. (Cl. 259—1)

The present invention relates to a local vibrator for 15 concrete, the tool of said vibrator being inserted into the concrete and left therein.

The usual vibrating devices are directly applied to the outer side of the form. However said devices in general produce an inadequate vibration which does not reach the central zone of the concrete mass which is to be vibrated, nor does the vibration reach the opposite and farthest zone of said mass. If the intensity of vibration is increased in order to reach the aforesaid central or farthest zone, this increase, which must be made near to the form, affects the structure of the concrete.

There are also known vibrators which are inserted within the mass of the concrete and provided with a remote control consisting either of a flexible shaft or a pneumatic or hydraulic drive system. However said systems produce some difficulties when the vibrating tool is to be recovered, and they are not suitable for operation deep inside the mass.

The object of this invention is that of obviating the aforementioned drawbacks by a local vibration system which permits the vibrator tool to be left within the vibrated mass, said tool being inexpensive and such as not to damage the features of the casting.

It is thus possible to use dry concretes, containing a minimum percent of water, the advantages of which are well known.

The vibrators according to this invention are completely embedded in the concrete, while the vibrating apparatus is arranged outside the form, so as to permit the aforementioned possibility either of recovering said tool or leaving it within the concrete when the vibration has been completed.

In the vibrating device according to this invention, the vibrating tool is inserted into the form through holes pre-disposed in the elements forming the form, while the vibrating device is fixed outside said form.

The vibrating tool can have different shapes, depending on the dimensional and qualitative features of the mass to be vibrated and according to the magnitude and to the frequency of the vibrations to be used. Generally said tool has one or more blades welded to one another at different angles, so as to ensure sufficient rigidity for the transmission of the vibrations and also for minimizing the occupied volume when the tool is to be abandoned after its use instead of being extracted through the insertion hole after the vibration has been completed.

One preferred form of embodiment could be that of an outer vibrator, operated in any manner suggested by the art and applied to the outside of the form, either directly or by means of an independent support.

This invention will be better understood from the following specification taken in connection with the drawing wherein is shown a detail cross-sectional view of a form provided with the vibrating device according to this invention.

With reference to the drawing, 1 is the form which can be made either of wood or metal, said form being

2

provided with an aperture 2 for the application of the vibrating apparatus.

Said vibrating apparatus comprises first the vibrating device 3. Said device needs is provided with a number of spokes or radial projections 4 for securing the device to the form by means of bolts (not shown in figure), so that the working vibrating shaft of the device 3 registers with the aperture 2 in the form 1.

The vibrating shaft projecting from the device 3 comprises a cylindrical portion 5, the outer surface of which is preferably smooth, and an extending portion 6, this latter being cylindrical and preferably of less diameter than cylindrical portion 5 and threaded on its outer surface.

On the smooth portion 5 can be positioned a sleeve 7, the length of which corresponds to the thickness of the form, the inside diameter of said sleeve being such that it will allow the vibration of the vibrating shaft. Said sleeve is also provided either with a circular flange or with a number of spokes 8 allowing the sleeve to be applied to the form. The end of the sleeve 7 which corresponds to the inner surface of the form is provided with one or more teeth 9 (only one of which is shown in figure) the use of which will be later described.

On the threaded end 6 of the vibrating shaft can be threaded a sleeve 10 to which is connected the vibrating tool or blade 11, formed by a metallic blade reinforced by a central rib, so as to have the necessary rigidity for the vibration; also, said tool can be formed by a star shaped section iron. The edge of the sleeve 10 turned towards the inside of the form is provided with a slot 12 into which tooth 9 fits so as to prevent the parts from rotating relative to each other when the sleeve 10 abuts the sleeve 7.

Having thus described the parts of this apparatus, as far as their embodiment is concerned, the operation of said apparatus is as follows:

The unit is predisposed for operation when the device 3 is still spaced apart from the form. The sleeve 8 is fitted on the cylindrical portion 5 of the working shaft and then sleeve 10 is threaded on the threaded end 6 of said shaft. Then, the vibrating tool 11 is inserted through the aperture 2 of the form 1, obviously at a level above that attained by the concrete inside the form. The insertion continues until the spokes 4 of the device 3 come into contact with the outer surface of the form. By causing the sleeve 7 to slide on the shaft 5, it is inserted through the aperture 2 until its front end contacts the sleeve 10, the tooth 9 of the sleeve 7 being thus inserted into the slot 12 of the sleeve 10. In this condition, when the annular flange 8, or the spokes which replace said flange, have been fixed on the form 1, the unit is ready for operation.

The form is filled until the level of the vibrating tool 11 has been exceeded by the suitable amount, and the concrete is vibrated. When the vibration has been carried out, if the concrete is still fluid to a sufficient extent to allow the vibrating tool to be extracted, if this is desired, the unit is extracted as a whole, by disconnecting both the flange 8 and the spokes 4. On the contrary, if either the concrete has a compactness which will not permit the tool 11 to be extracted, or it is deemed not suitable to extract said tool, it is abandoned within the vibrated mass and the driving portion is disconnected by disengaging the spokes 4 from the form 1 and leaving the annular ring 8 engaged with the form. In this way the engagement between the sleeve 7 and the sleeve 10 is maintained so that this latter is prevented from rotating by the tooth 9 which is inserted within the slot 12. Then the vibrating device 3 is rotated so as to unscrew the threaded portion 6 from the sleeve 10, so as to allow the vibrating device to be extracted together with its

shaft, while the vibrating tool 11 and sleeve 10 are abandoned within the concrete.

This way it is possible, for instance, to vibrate a pillar of concrete at different heights obtaining a remarkably better result while the cost of the vibrating tool abandoned within the mass is such as will not affect the economy of the work.

I claim:

1. A concrete vibrator comprising a concrete form having an aperture therein, a vibration producing means which can be placed against the outside of said concrete form, a vibrating tool insertable through the aperture in said concrete form for vibrating concrete within said form, and means between said vibration producing means and said vibrating tool flush with the surface of the concrete on the inner face of the concrete form for connecting said tool to the vibration producing means and permitting disconnecting of said tool from said vibration producing means.

2. A concrete vibrator comprising a concrete form having an aperture therein, a vibration producing means which can be placed against the outside of said concrete form and having a threaded end thereon sufficiently long to extend through the form, a vibrating tool insertable through the aperture in said concrete form for vibrating concrete within said form, connecting means attached to said vibrating tool into which connecting means said threaded end is threaded, said connecting means being flush with the surface of the concrete on the inner face of the concrete form, and sleeve means insertable into said form for retaining said connecting means in said concrete when said vibration producing means is unscrewed from said connecting means.

3. A concrete vibrator comprising a concrete form having an aperture therein, a vibration producing means which can be placed against the outside of said concrete form and having a threaded end thereon sufficiently long to extend through the form, a vibrating tool insertable through the aperture in said concrete form for vibrating concrete within the form, a connecting sleeve attached to said vibrating tool and having a threaded bore therein receiving said threaded end on said vibration producing means, the end of said connecting sleeve opposite the vibrating tool being flush with the concrete on the inner surface of the form, and a retaining sleeve with a diameter at least as small as the diameter of said connecting sleeve and having a bore therethrough sufficiently large to receive the threaded end of said vibration producing means, said retaining sleeve being insertable through the form.

4. A concrete vibrator comprising a concrete form having an aperture therein, a vibration producing means which can be placed against the outside of said concrete

form and having a threaded end thereon sufficiently long to extend through the form, a vibrating tool insertable through the aperture in said concrete form for vibrating concrete within the form, a connecting sleeve attached to said vibrating tool and having a threaded bore therein receiving said threaded end on said vibration producing means, the end of said connecting sleeve opposite the vibrating tool being flush with the concrete on

10 the inner surface of the form, and a retaining sleeve with a diameter at least as small as the diameter of said connecting sleeve and having a bore therethrough sufficiently large to receive the threaded end of said vibration producing means, said retaining sleeve being insertable through the form, a flange on said retaining sleeve for securing said sleeve against rotation in the form, and means on said retaining sleeve cooperating with said connecting sleeve for preventing rotation of said connecting sleeve relative to said retaining sleeve.

5. A concrete vibrator comprising a concrete form having an aperture therein, a vibration producing means which can be placed against the outside of said concrete form and having a threaded end thereon sufficiently long to extend through the form, a vibrating tool insertable through the aperture in said concrete form for vibrating concrete within the form, a connecting sleeve attached to said vibrating tool and having a threaded bore therein receiving said threaded end on said vibration producing means, the end of said connecting sleeve opposite the vibrating tool being flush with the concrete on the inner surface of the form, and a retaining sleeve with a diameter at least as small as the diameter of said connecting sleeve and having a bore therethrough sufficiently large to receive the threaded end of said vibration producing means, said retaining sleeve being insertable through the form, a flange on said retaining sleeve for securing said sleeve against rotation in the form, and teeth on said retaining sleeve, said connecting sleeve having recesses therein for receiving said teeth.
